CLAIM

The ornamental design for a controller for an X-ray camera for medical treatment, as shown and described.

DESCRIPTION

FIG. 1 is a front, top and left side perspective view of a controller for an X-ray camera for medical treatment, showing my new design;

FIG. 2 is a top plan view thereof;

FIG. 3 is a front elevational view thereof;

FIG. 4 is a rear elevational view thereof;

FIG. 5 is a bottom plan view thereof;

FIG. 6 is a left side elevational view thereof;

FIG. 7 is a right side elevational view thereof;

FIG. 8 is a front, top and left side perspective view of a second embodiment of the controller for an X-ray camera for medical treatment;

FIG. 9 is a top plan view thereof;

FIG. 10 is a front elevational view thereof;

FIG. 11 is a rear elevational view thereof;

FIG. 12 is a bottom plan view thereof;

FIG. 13 is a left side elevational view thereof; and,

FIG. 14 is a right side elevational view thereof; the dotted lines shown in FIGS. 8-14, together with FIG. 14 being for illustrative purposes only and forming no part of the claimed design.
